UNITED STATES PATENT OFFICE.

MICHAEL B. BOWEN, OF DECATUR, ILLINOIS, ASSIGNOR TO FARIES MANUFACTURING COMPANY, OF DECATUR, ILLINOIS, A CORPORATION OF ILLINOIS.

DESIGN FOR A TABLE LAMP.

Application filed January 19, 1926. Serial No. 16,169. Term of patent 7 years.

To all whom it may concern:

Be it known that I, MICHAEL B. BOWEN, a citizen of the United States, residing at Decatur, in the county of Macon and State of Illinois, have invented a new, original, and ornamental Design for Table Lamps, of which the following is a specification, reference being had to the accompanying drawing, forming part thereof.

The figure is a view in perspective, showing my new design.

I claim:

The ornamental design for a table lamp, as shown.

MICHAEL B. BOWEN.
